(57) **CLAIM**

The ornamental design for a self-cleaning part of a docking station for cleaning appliance as shown and described.

DESCRIPTION

The patent or application file contains at least one drawing executed in color. Copies of this patent or patent application publication with color drawing(s) will be provided by the Office upon request and payment of the necessary fee.

1. Self-cleaning part of docking station for cleaning appliance

2. Self-cleaning part of docking station for cleaning appliance
